CLAIM

The ornamental design for a mattress pad configuration, as shown and described.

DESCRIPTION

FIG. 1 is a top perspective view of a mattress pad configuration of the present invention;

FIG. 2 shows a top plan view thereof (with the bottom thereof forming no part of the claimed design);

FIG. 3 is a left end elevational view (the right side being the same);

FIG. 4 is a near side elevational view of that which is shown in FIG. 1 (the far side elevational view being a mirror image thereof); and,

FIG. 5 is an enlarged fragmentary top plan view thereof of the section within the dashed lines in FIG. 2.
